PORTABLE OSCILLOSCOPE OR SIMILAR ARTICLE

John H. Hanke, Wayne, N.J., assignor to Champion Spark Plug Company, Toledo, Ohio, a corporation of Delaware

Application March 26, 1959, Serial No. 55,195

Term of patent 14 years

(Cl. D26—1)

FIG. 1.

FIG. 3.

FIG. 4.

FIG. 2.

Fig. 1 is a perspective view of the portable oscilloscope embodying my new design;

Fig. 2 is an elevation of one side of the portable oscilloscope. The opposite side is of the same configuration;

Fig. 3 is a rear end view thereof; and

Fig. 4 is a front end view thereof.

The dotted line portion is shown for illustrative purposes only.

I claim:

The ornamental design for a portable oscilloscope or similar article, substantially as shown and described.
